UNITED STATES PATENT OFFICE

157,139

JEWEL CASE

Philip Fox, Bala, Pa.

Application March 30, 1948, Serial No. 145,449

Term of patent 7 years

(Cl. D86—9)

To all whom it may concern:

Be it known that I, Philip Fox, a citizen of the United States, residing at Bala, in the county of Montgomery and State of Pennsylvania, have invented a new, original, and ornamental Design for Jewel Cases, of which the following is a specification, reference being made to the accompanying drawing, forming part thereof, in which:

Figure 1 is a side elevation of a jewel case embodying my design, the same being shown with the petal parts in a closed position;

Fig. 2 is a top or plan view of the same, but with the petal parts in open position; and

Fig. 3 is a sectional view along line 3—3 of Fig. 2.

I claim:

The ornamental design for a jewel case, as shown.

PHILIP FOX.
